(57) **CLAIM**

The ornamental design for a wound dressing, as shown and described.

DESCRIPTION

FIG. 1 is a perspective view of a wound dressing showing our new design;
FIG. 2 is a top plan view thereof;
FIG. 3 is a bottom plan view thereof;
FIG. 4 is a front plan view thereof;
FIG. 5 is a left side elevational view thereof;
FIG. 6 is a rear elevational view thereof;
FIG. 7 is a right side elevational view thereof;
FIG. 8 is a perspective view of a second embodiment of a wound dressing showing our new design;
FIG. 9 is a top plan view thereof;
FIG. 10 is a bottom plan view thereof;
FIG. 11 is a front plan view thereof;
FIG. 12 is a left side elevational view thereof;
FIG. 13 is a rear elevational view thereof; and,
FIG. 14 is a right side elevational view thereof.
In the drawings, the broken lines depict environmental subject matter only and form no part of the claim.

1 Claim, 8 Drawing Sheets

Related U.S. Application Data

continuation of application No. 29/625,440, filed on Nov. 9, 2017, now abandoned.
